PRODUCTION OF HOSIERY

Erich Eissner, Chemnitz, Germany, assignor to
 Karl Lieberknecht G. m. b. H., Oberlungwitz,
 Saxony, Germany

Application September 20, 1935, Serial No. 41,477
 In Germany October 6, 1934

5 Claims. (Cl. 66—186)

This invention relates to a method of producing tubular hosiery having a heel better adapted to the form of the human heel than a pouch heel on circular knitting machines.

5 The invention attains its object by providing a method according to which after the formation of a heel portion having uniform width a narrower heel portion having the same width throughout is produced whose border loops are 10 subsequently united with the free portions of the last course of the broader heel portion, the border loops of which are then united with the free portions of the first course of the tubular foot part.

15 The application of this method insures an accumulation of material at the point where the human heel requires it while the goods are still on the machine and without any distortion of meshes.

20 The edges of the heel portions are preferably united by looping, and the hosiery produced on the machine up to the toe is therefore removed from the machine and the portions to be united are then transferred to a looping machine. To 25 facilitate looping the free portions of the broader heel portion or of the tubular foot part, which are disposed in front of and behind the narrower heel part, are provided, according to the invention, with auxiliary pieces consisting of courses 30 of inferior material to be removed after the transfer.

By way of example, the invention is illustrated in the accompanying drawing which discloses the main phases of the method and in which 35 Figure 1 shows a part each of a leg and a foot portion connected therewith and a heel portion provided between these two members and, further, two auxiliary pieces arranged at both long sides thereof and prior to being cut, the entire view being in perspective; Fig. 2 shows the parts represented in Fig. 1, but with the auxiliary pieces cut; and Fig. 3 is a view of a finished sock made according to the invention.

The manner of operation according to the new 40 method is as follows: The leg 1 is worked in known manner on a circular knitting machine down to its end by causing the needle cylinder to carry out full revolutions. After completion of the leg 1 a part of the needles having worked 45 the leg are rendered inoperative but retain the loops hanging thereon. Work is then continued with the needles that have remained in operative position and with the thread guide used for the leg. The needle cylinder carries out an oscillating motion, and gradually a narrow piece is

thus produced which constitutes the broad heel portion 2 and which, owing to the oscillating motion of the needle cylinder, is provided on its lateral edges with regular border loops.

5 After completion of the broad heel portion 2 some of the needles having worked it are also rendered inoperative on both sides, i. e., those that carry the portions 2', 2'', and also retain the loops last formed and still hanging thereon. The needle cylinder continues to carry out an 10 oscillating motion, and with the same thread guide that has worked the leg 1 and the portion 2 the still narrower portion 3 is now knit.

15 When the last course of the portion 3 is completed, the thread guide is stopped like the 15 needles on which the portion 3 is disposed, whilst the needles carrying the courses 2', 2'' are started. To the courses 2', 2'', by means of a special thread guide for each of them, auxiliary 20 courses 4, 4' are worked, the number of these courses being preferably less than that of the courses in the narrowest portion 3.

25 After completion of the auxiliary courses 4, 4' the two special thread guides having worked them are rendered inoperative again, and the non-operative thread guide that has worked the narrowest portion 3 is started again together with all needles of the cylinder. While the cylinder rotates the foot 5 is worked to the end in known manner and then thrown off. 30

The auxiliary courses 4, 4' positioned between the last courses 2', 2'' of the portion 2 and the first courses 5', 5'' of the foot 5 are then cut, whereby the fabric shown in Fig. 2 is produced.

35 Then the border wale 3' with the course 2' and the border wale 3'' with the course 2'' are transferred to the needles of a looping machine and connected by placing each loop on a needle. To facilitate this transfer the auxiliary courses 4, 4' are provided which are afterwards removed. 40

The next step consists in transferring a border wale of the portion 2 with the course 5' and the other border wale of the portion 2 with the course 5'' to a looping machine and regularly joining them. The auxiliary courses 4, 4' serve again to facilitate this operation and are removed later on.

45 The toe of the stocking is looped in known manner and need not be described in detail. 50

Instead of working after completion of the portion 2 the portion 3 and then the auxiliary courses 4, 4', as described above, it is also possible to produce first the courses 4, 4' and then the portion 3, or the portion 3 as well as the 55

auxiliary courses 4, 4' may be simultaneously worked with three thread guides. Finally, the auxiliary courses 4, 4' may be omitted entirely, which, however, is not advisable, as good and accurate transfer of the courses at the end of portion 2 and at the beginning of the foot 5 is prevented thereby. The invention includes of course these modifications also.

It is immaterial whether the heel, the high heel and the foot portions are reinforced, as it is merely necessary to choose the number of thread guides operating at a time accordingly.

I claim:—

1. Method of producing tubular hosiery, consisting in knitting the leg by circular knitting, knitting broad and narrow heel portions by oscillating knitting, knitting the foot portion by circular knitting and then looping the narrow and broad heel portions together and the broad heel portion to the foot portion.

2. Method of producing tubular hosiery, consisting in knitting the leg by circular knitting, knitting broad and narrow heel portions and auxiliary portions by oscillating knitting, knitting the foot portion by circular knitting, the narrow heel portion and auxiliary courses being integrally joined to the first course of the foot portion, cutting the auxiliary portions and then looping the narrow and broad heel portions together and the broad heel portion to the foot portion and finally removing the auxiliary courses.

3. Method of producing tubular hosiery, consisting in knitting the leg by circular knitting, stopping a part of the needles which retain the loops hanging thereon, knitting a broad heel portion with the still operating needles by oscillating knitting, stopping again a part of the needles which also retain the loops formed thereon, knitting a narrow heel portion by oscillating knitting, stopping the needles working the

narrow heel portion after completion of same, starting again the second set of needles stopped, knitting auxiliary courses to the broad heel portion by oscillating knitting with two special thread guides, stopping again the two special thread guides and starting the first thread guide, starting all needles and knitting the foot portion by circular knitting, removing the goods from the machine, cutting the auxiliary courses, transferring the last courses of the broad heel portion with the border wales of the narrow heel portion to a looping machine and looping them together, removing the auxiliary courses at the last courses of the broad heel portion, transferring the first courses of the foot portion and the border wales of the broad heel portion to a looping machine and looping them together and removing the auxiliary courses also from the foot portion.

4. Method of producing tubular hosiery, consisting in knitting the leg by circular knitting, knitting a broad heel portion by oscillating knitting, knitting two auxiliary portions by oscillating knitting, knitting a narrow heel portion between the auxiliary portions, knitting the foot portion by circular knitting, cutting the auxiliary portions, joining the narrow and broad heel portions to the foot portion after transfer to a looping machine and removing the auxiliary portions.

5. Method of producing tubular hosiery, consisting in knitting the leg by circular knitting, knitting a broad heel portion, simultaneously knitting a narrow heel portion and two auxiliary portions on both sides of the narrow heel portion with a thread guide for each of them, knitting the foot portion by circular knitting, cutting the auxiliary portions, joining the narrow and broad heel portions to the foot portion after transfer to a looping machine and removing the auxiliary portions.

ERICH EISSNER.
